PROFESSIONAL CABINET

George E. Froelich, Two Rivers, Wis., assignor to
Hamilton Manufacturing Company, Two Rivers, Wis., a corporation of Wisconsin

Application July 25, 1942, Serial No. 452,304

4 Claims. (Cl. 312—151)

This invention relates to professional cabinets more particularly for dental use and of the class providing a top working surface and a bottle rack portion at the rear of the working surface.

It is desirable to have the bottle rack portion normally enclosed to guard against dust and breakage and yet when the bottles are disclosed to have them substantially in the plane of the working surface so that the hands of the operator may move from the working surface to the bottle compartment and vice versa, substantially in a horizontal plane and without making it necessary for the operator to reach either up or down for the bottles.

The present invention is an improvement on my Patent No. 2,242,720, issued May 20, 1941, for "Professional cabinet," in which I broadly disclosed an inverted box-like cover for the rack portion having a rear wall, a plunger fixed to the rear wall of the cover and extending below the working surface, guide means for the plunger, and a counterbalancing device for the cover and plunger within the cabinet below the working surface whereby the cover may be readily elevated above the bottle rack portion supported solely by the plunger.

In said patent, however, the cover for the rack portion of the cabinet was shown projecting materially above the working surface of the cabinet both in its lowered and elevated positions, thus constituting an obstruction to ready use of the cabinet from the rear thereof. Since it is advantageous to embody a construction of this class in a cabinet which is mobile, as by having wheels thereon, to enable it to be placed say in the center of the floor of the dental operating room conveniently adjacent both to the patient's chair and the dentist's working position, it is desirable that when the bottle rack is not in use, for example, the entire cabinet top including both the working surface and the bottle rack portion be substantially flush, and that the cover of the bottle rack portion be elevated materially above the working surface only when the cover is in its raised position to disclose the bottles.

The present invention aims to provide a construction in which the bottle rack constitutes substantially a horizontal continuation of the working surface when the cover is elevated while permitting the cover to be substantially flush with the working surface when it is closed, and to this end it is contemplated by the present invention that the bottle rack be carried by the cover itself and be reciprocable with the cover.

Among other objects the present invention aims to provide an improved device of this class in which the operating parts occupy a minimum of space while ensuring enhanced smoothness and precision of operation.

The foregoing and other objects and advan-

tages will be apparent from the following description, taken together with the accompanying drawings, in which—

Figure 1 is a partial perspective view of a cabinet embodying the present invention, showing, in broken lines, the cover and bottle rack in elevated position and in full lines these parts in closed or normal position;

Figure 2 is an enlarged partial longitudinal sectional view of the cover and bottle rack and the operating mechanism therefor, and being a section taken on the line 2—2 of Fig. 1 and 2—2 of Fig. 3;

Figure 3 is a cross-section taken on the staggered line 3—3 of Fig. 2; and

Figure 4 is a detail view and being a fragmentary section taken on the staggered line 4—4 of Fig. 3, partially in elevation.

Referring specifically to the illustrative construction shown in the drawings, the cabinet 10, the top portion only of which need be here shown, has an upper horizontal working surface 11, side walls 12 and 13, and rear wall 14. At the front of the cabinet the usual drawers 15 may be accessible. The working surface 11 is advantageously of suitable sanitary stainproof material and has a slightly raised rim 16 to prevent articles from rolling off thereof. The working surface 11 is preferably disposed, by reason of the height of the cabinet, conveniently for use when the operator is in standing position.

Just to the rear of the working surface 11 is the bottle rack portion 17 of the cabinet, with which this disclosure is chiefly concerned, and in accordance with the present invention, in the interior of the cabinet, between the main part thereof in which the drawers 15 are located and the bottle rack portion, may be located an interior wall 18 parallel with the rear wall 14 and extending downwardly to a horizontal partition 19. Vertically reciprocal in the bottle rack portion 17 I have shown a bottle rack 20 carried by a cover 21 which has a rear wall 22. These parts just referred to may be suitably constructed of wood or other non-metallic material in order to save metal.

The cover 21 and bottle rack 20 are here shown carried by a single plunger or support 23 which may be in the form of a metallic channel member having a web 24 and side flanges 25. At its upper end the channel member 23 may be bent over as at 26 to underlie the bottle rack 20 to which it may be secured as by screws 27 for common reciprocal movement of the plunger, bottle rack and cover in the bottle rack portion or vertical space between the interior wall 18 and rear wall 14 of the cabinet. The single plunger 23 is shown disposed centrally of the length of the cover 21 which preferably terminates short of the sides 12 and 13 of the cabinet so that the cover

is guided somewhat at each end as by the overhanging portion 28 of each of the side walls, the end walls 29 of the cover riding freely between these overhanging parts 28. The end walls 29 may also depend below the bottle rack 20, as best shown in Fig. 2, and may rest on the platform 30 through the intermediation of pads 31 when the cover and rack are in lowered position. The platform 30 may be apertured as at 32 to pass the plunger 23 snugly but slidably therethrough, and this platform also serves somewhat as guide means for the plunger and may thus define the lower limit of the cabinet bottle rack portion 17.

For counterbalancing the cover and rack, the interior wall 18 has fixed thereto, as by screws 33, a pivot bracket 34 to the web 35 of which is pivoted as at 36, intermediate its length, the counterbalancing lever 37, one end of which is articulated as at 38 with a link 39 articulated at 40 with the plunger 24. The other end of the counterbalancing lever 37 has a flat foot 41 which in one position is adapted to abut the padded block 42 which is secured as by a screw 43 to the upper surface of the horizontal partition 19. An expansion coil spring 44 is hooked at one end, as at 45, to the counterbalancing lever 37 adjacent the articulation 38, and, at its other end, as at 46, to an eye-screw 47 which may be fixed on the interior wall 18. Another expansion coil spring 48 is here shown hooked at one end, as at 49, to the counterbalancing lever 37 adjacent this foot 41, and, at its other end, as at 50, to an eye-screw 51 fixed to the horizontal partition 19. Springs 44 and 48 are arranged so that they are under tension when the counterbalancing lever 37 is rotated on its pivot 36 to depress the plunger 24, so that the natural resilience of these springs tends to elevate the plunger and with it the bottle rack 20 and cover 21, limited by the engagement of the lever foot 41 with the stop block 42, the springs 44 and 48 thus constituting with the lever 37 actuating means disposed in a plane extending in the direction of the greatest dimension of the rack.

To releasably retain the plunger, and with it the rack and cover, in depressed position, the plunger is shown having a locking surface or lug 52 adjacent its lower end, struck-out from its web 24, and engageable by the locking lip 53 of a rockable catch-piece 54. The catch-piece 54 is here shown mounted on the web 55 of a bracket 56 secured as by screws 57 to the interior wall 18, this wall being conveniently cut away as at 58 to permit the catch-piece 54 to play in this opening with its tail 59 extending therethrough. The opening 58 also affords access to the mechanism as a whole, for oiling or adjustment purposes. The plunger is fixed to the cover 21 through the intermediation of the rear wall 22, and this rear wall, which together with the cover and bottle rack forms a somewhat box-like formation about the bottles, also serves to protect the bottles when the bottle rack is elevated.

To mount the catch-piece 54 rockably on the bracket 56 the bracket may have a stud 60 riveted thereto and which passes loosely through a perforation in the catch-piece, a compression coil spring 61 being inserted between the head of the stud 60 and the catch-piece to urge the catch-piece and bracket together into a position shown in Fig. 3, in which the locking lip 53 of the catch-piece overhangingly engages the lug 52 of the plunger support 23 and thus holds the bottle rack and cover in depressed position as shown in full lines in Figures 1 and 3 against the force of the

springs 44 and 48, these springs being at this time stretched as shown in broken lines in Fig. 2 and thus ready to elevate the bottle rack 20 and cover 21 to the position shown in full lines in Fig. 2 and in the dotted lines in Figs. 1 and 3, when the catch 54 is released.

To release the catch I have provided a depressible rod 62 which is carried by the tail 59 of the catch-piece 54 as by having a reduced lower end 63 which passes through a perforation in this part of the catch-piece. A light coil spring 64 is desirably interposed on the reduced end 63 of the rod 62 between the tail 59 and a washer 65, to prevent chattering of the rod. At its upper end, the rod 62 emerges slightly above the working surface 11 just in front of the bottle rack portion 17 in a button-like extremity 66. When the button 66 is depressed by the finger of the operator the catch-piece 54 is thus rocked to the left (Fig. 3) on the stud 60 and the locking lip 53 of the catch-piece is released from the lug 52 to permit the springs 44 and 48 to rotate the counterbalancing lever 37 to elevate the bottle rack and cover as already described. The catch-piece 54 is guided in its rocking movement by the channel 67 of the bracket 56 and by notch 68 in the opening 58 of the interior wall 18.

To prevent jarring of the bottles (such as the bottle 69) on the bottle rack 20 when the latter is elevated as described, I provide shock absorbing means such as the air check mechanism 70, which may comprise a cylinder 71 mounted on a nipple bracket 72 secured as by screws 73 on the horizontal partition 19. At its upper end the cylinder may have a closure gland 75 in which reciprocates the piston rod 76 of the piston 77, the piston rod being dependently secured to bottle rack 20 as by screw 78 which passes through the bent-over part 36 of the plunger 23 to be threadedly received in the piston rod. A recess 79 in the underface of the bottle rack accommodates the head of the screw 78.

As the plunger is elevated, in the manner already described, the piston 77 moves upwardly 45 simultaneously and compresses the air in the upper part of the cylinder thus preventing too rapid upward movement under the influence of the springs 44 and 48. The cylinder 71 may have a small bleed port 80 adjacent its upper end so as to permit the compressed air to be expelled retardedly therethrough and thus permit the bottle rack to be elevated to its uppermost position as determined by the stop members 41 and 42 in conjunction with the counterbalancing lever 37. The port 80 may also be used for oiling purposes. The slot 100 in the plunger 23 permits access through the opening 58 to the port 80.

Any suitable piston arrangement may be employed, one operable form of which is shown in Fig. 4 in which the piston rod 76 is reduced at its lower end 85 to have this end passed through a pair of washers 81 and 82 which clamp between them, by means of the nut 84, a cup 77 of leather or like material which reciprocates in the cylinder 71. The rod end 85 is shown threaded to receive the nut 84. The lower end of the cylinder 71 is closed except for an air adjustment vent 86 which is threaded to receive and is partially closed by an adjustment screw 87 having a tapered longitudinal groove 88 therein. During the upward stroke of the piston, the cup 77 makes a substantially sealing contact with the inner walls of the cylinder 71, and the air adjustment screw 87 may be suitably adjusted to prevent undue suction below the piston.

During reverse or downward movement of the piston, as is well understood in the use of such air check devices, air in the cylinder is permitted to pass by the piston cup 17 to permit return of the piston to its lowered position to close the cover 21 as shown in full lines in Figs. 1 and 3, with the cover substantially flush with the working surface 11 and the bottles 69 concealed and protected.

When the cabinet part or cover 21 is manually depressed as just described, it is pushed down until the plunger lug 52 engages under the lip 53 of the catch, the lip 53 having a flared cam surface 91 which permits the lug 52 to momentarily rock the catch 54 on its stud 60 to permit the lug 52 to pass therebelow. Thereafter the spring 61 returns the catch to holding position in which the lip 53 takes over the lug 52 and holds the plunger 23 and with it the depressible cabinet part 20 and 21 in the position shown in full lines in Fig. 3 until the button 66 is again manually pressed.

The bottles such as 69, in the elevated position of the cover, are readily accessible to the operator through the open side 92 of the cover, the bottle rack 20 being then substantially in the plane of the working surface 11.

As best shown in Figs. 3 and 4 the plunger 24 may be further guided in its reciprocating movement by a collar 89 of wood or the like secured to the foot of the plunger as by screws 90 and encircling the exterior of the cylinder 71 for upward and downward sliding movement thereon.

Such changes may be made as fall within the scope of the appended claims without departing from the invention.

Having described my invention, I claim:

1. In a cabinet of the class described having a working surface and an elevatable and depressible bottle rack at the rear of said working surface, that improvement therein comprising a central plunger supporting the bottle rack and depending within the cabinet, a partially closed cylinder fixed in the cabinet vertically aligned with the plunger, the plunger being of channel formation and having vertical side walls between which the cylinder is located, a collar at the lower end of the plunger through which the cylinder passes, the collar being slidably movable on the cylinder for guiding the plunger in its vertical movement, a piston depending from the bottle rack received within the cylinder and having a piston head thereon resistingly movable in the cylinder to provide with the cylinder a fluid shock absorber device, spring means for elevating the plunger and bottle rack against the retarding action of the shock absorber device, a locking element adjacent the lower end of the plunger, a resiliently rockable catch-piece carried within the cabinet and having a locking lip engageable by the said locking element to releasably hold the plunger and bottle rack in depressed position against the action of said spring means, and a member having its upper end adjacent said working surface and its lower end in position to rock the catch-piece to releasing position upon movement of said member.

2. In a cabinet of the class described having a working surface and an elevatable and depressible bottle rack at the rear of said working surface, that improvement therein comprising a

central plunger supporting the bottle rack and depending within the cabinet, a partially closed cylinder fixed in the cabinet vertically aligned with the plunger, a collar at the lower end of the plunger through which the cylinder passes, the collar being slidably movable on the cylinder for guiding the plunger in its vertical movement, a piston depending from the bottle rack received within the cylinder and having a piston head thereon resistingly movable in the cylinder to provide with the cylinder a shock absorber device, resilient means for elevating the plunger and bottle rack against the retarding action of the shock absorber device, a locking element adjacent the lower end of the plunger, a resilient catch-piece of the floating type carried within the cabinet and having a locking lip engageable by the said locking element to releasably hold the plunger and bottle rack in depressed position against the action of said resilient means, a tail on the catch-piece, a member carried by the cabinet in position to engage said tail to move the catch-piece to releasing position upon movement of said member, and a spring carried by said member engaging the said tail.

3. In a cabinet of the class described having a working surface and an elevatable and depressible rack adjacent said working surface, that improvement therein comprising a central plunger supporting the rack and depending within the cabinet, a partially closed cylinder fixed within the cabinet, a piston depending from the rack received within the cylinder and having a piston head thereon resistingly movable in the cylinder to provide with the cylinder a shock absorber device, guiding means carried by the cabinet at least in part through the intermediation of the plunger for guiding the plunger and piston in their vertical movement, actuating means including a tension coil spring and a lever disposed in a plane extending in the direction of the greatest dimension of said rack for elevating the plunger and rack against the retarding action of the shock absorber device, locking elements within the cabinet to releasably hold the plunger and rack in depressed position against the action of said actuating means, and a member carried by the cabinet for releasing said locking elements.

4. In a cabinet of the class described having a working surface and an elevatable and depressible bottle rack adjacent said working surface, that improvement therein comprising a single central plunger supporting the bottle rack and depending within the cabinet, a partially closed cylinder fixed within the cabinet, a piston depending from the bottle rack received within the cylinder and having a piston head thereon resistingly movable in the cylinder to provide with the cylinder a shock absorber device, guiding means carried by the cabinet at least in part through the intermediation of the plunger for guiding the plunger and piston in their vertical movement, actuating means for elevating the plunger and bottle rack against the retarding action of the shock absorber device, locking elements within the cabinet to releasably hold the plunger and bottle rack in depressed position against the action of said actuating means, and a member carried by the cabinet for releasing said locking elements.

GEORGE E. FROELICH.
